(No Model.)

E. F. LEBLOND.

MACHINE FOR PREPARING AND DISTRIBUTING TOBACCO.

No. 290,333.

Patented Dec. 18, 1883.

UNITED STATES PATENT OFFICE

EUGÈNE FERDINAND LEBLOND, OF PARIS, FRANCE.

MACHINE FOR PREPARING AND DISTRIBUTING TOBACCO.

SPECIFICATION forming part of Letters Patent No. 290,333, dated December 18, 1883.

Application filed May 29, 1883. (No model.) Patented in France April 2, 1883, No. 154,733; in England April 9, 1883, No. 1,775, and in Belgium April 10, 1883, No. 61,037.

To all whom it may concern:

Be it known that I, EUGÈNE FERDINAND LEBLOND, a citizen of France, residing at Paris, in the Republic of France, have invented new and useful Improvements in Mechanism for Preparing Tobacco for Cigarette-Machines, (for which I have obtained a patent in France for fifteen years, No. 154,733, bearing date April 2, 1883; in Great Britain for fourteen years, dated April 9, 1883, No. 1,775; and in Belgium for fifteen years, dated April 10, 1883, No. 61,037,) of which the following is a specification.

My invention relates to mechanism for preparing tobacco for cigarette-machines. The mechanism referred to comprises an endless band having continuous motion, upon which band the tobacco is thrown or otherwise placed in greater or less order. A fixed glass or other smooth surface placed above the band equalizes the tobacco in its passage and assists in forming it into a cake, which is then delivered intermittently in equal lengths to the cigarette-machine or molding apparatus for filling into paper tubes.

In the accompanying drawings, Figure 1 shows a vertical section, and Fig. 2 a plan, of my machine. Fig. 3 shows detail views of the pinion *m* and its attachments.

30 *a* is the endless band, which is continuously drawn by one of two rollers, *b* *c*, around which it is placed. Above this band is held the slab *d*, of glass or other substance which is smooth, so as to allow the tobacco to glide freely under its lower face, which is or may be parallel with the endless band. The distance between the slab *d* and the endless cloth may be regulated at pleasure.

In front of the slab *d* is hung the feeding-cylinder *f*, the lower side of which is on a level with the lower face of the slab *d*, and which compels the tobacco to follow the course of the endless band and to pass under the slab *d*. The cylinder *f* can be revolved by a belt or chain from the roller *c*, as indicated in Fig. 2, or by other means.

In rear of the slab *d* is hung another roller, *g*, which is covered with supple india-rubber. This roller *g* extends about half-way down

into the space between the band *a* and the slab *d*, and serves by its position, when stationary, as a barrier to the progress of the tobacco which is on the band *a*; but when the roller *g* is turned in the direction of the arrow *g'* it serves to further compress the end of 55 the cake of tobacco, and then to move this compressed end out as far as desired upon a fixed platform. The roller *g* is then again stopped, the projecting end of the cake detached by a knife or otherwise, and the roller 60 *g* then again turned, and so on. In order to promote these effects, the roller *g* is turned intermittently, the extent of its rotation being variable and governed in accordance with the greater or less size of the cigarettes to 65 be made. Thus the roller *g* turns in the direction of the arrow *g'* to deliver the compressed tobacco to the molding mechanism. The motion of said roller is then either reversed or arrested, so that it will again assist in the caking of the tobacco; and this alternate movement is repeated continuously. The tobacco is placed in front of the slab *d*, either by hand or is delivered from a duct or from a table placed in a transverse position with 70 the endless band, or it may be fed through a tube.

From the preceding description of the apparatus it is easy to understand that in order to produce an even and regular caking or 80 pressing together of the tobacco it suffices to either place, throw, or let fall the tobacco without any care on the endless band at the front end of the slab *d*. The intermittent rotary motion of the roller *g* may be produced 85 by different means—for instance, as indicated in Figs. 1, 2, and 3. In this form a ratchet-wheel, *i*, is affixed to the end of roller *g*, and a pawl, *j*, fitted upon the face of a pinion, *m*, (which is loose on the axle of the said roller,) 90 engages into said ratchet-wheel when it moves in the direction of the arrow *g'*. The pinion *m* meshes with a toothed wheel, *n*, which is loose on the shaft of the roller *b*. Into the teeth of the wheel *n* engages also a toothed sector, *p*, which 95 by a rod, *x*, is connected with a lever, *l*, which latter communicates with a cam of the driving-shaft of the cigarette-machine. The ar-

ticulation of the connecting-rod x and of the lever l allows of varying and regulating the movements of the sector p , and consequently the extent of the turning motion of the roller g .

5 In beginning the work, or while starting the machine, or even while it is working, it may be expedient to stop the distribution in order to give the tobacco-cake time to form. For that purpose the pawl j is either disengaged from the teeth of the ratchet-wheel i , in order to isolate and stop the roller g , or the wheel n may be disconnected from the sector p , or the connecting-rod x may be made of two pieces, $x x'$, (see Fig. 1,) jointed by a 15 coupling, v , which allows of breaking or re-establishing the connection at will.

The tobacco used may be ordinary loose tobacco cut into small flakes, slightly moistened, or may be of other kind.

I claim as my invention—

20 1. The combination of the endless band a , slab d , and rollers f and g , with mechanism, substantially as herein described, for moving said band continuously and said roller g intermittently, said roller g entering part way 25 into the space between said slab and said band, substantially as herein shown and described.

2. The combination of the endless band a , roller f , slab d , and roller g , with the ratchet-wheel i , pawl j , toothed wheels $m n$, toothed 30 sector p , rod x , and lever l , substantially as herein shown and described.

EUGÈNE FERDINAND LEBLOND.
